UNITED STATES PATENT OFFICE

101,474

DESIGN FOR A VANITY BOX OR SIMILAR ARTICLE

Theodore Sundin, New York, N. Y., assignor to Sagamor Steel Goods Corporation, Long Island City, N. Y., a corporation of New York

Application January 11, 1935, Serial No. 54,808

Term of patent 3½ years

To all whom it may concern:

Be it known that I, Theodore Sundin, a citizen of the United States of America and resident of Bronx, New York city, in the county of Bronx, State of New York, have invented a new, original, and ornamental Design for a Vanity Box or Similar Article, of which the following is a specification, reference being had to the accompanying drawing forming part thereof.

In the drawing:

Fig. 1 is a plan view of a vanity box or similar article, showing my design.

Fig. 2 is a front elevation of the same.

Fig. 3 is a side elevation of the same.

I claim:

The ornamental design for a vanity box or similar article, substantially as shown.

THEODORE SUNDIN.
